UNITED STATES PATENT OFFICE.

CHARLES E. FELT, OF CHICAGO, ILLINOIS.

BOTTLE-WASHING MACHINE.

1,023,830.

Specification of Letters Patent. Patented Apr. 23, 1912.

Application filed April 1, 1909. Serial No. 487,121.

To all whom it may concern:

Be it known that I, CHARLES E. FELT, a citizen of the United States, residing at Chicago, in the county of Cook and State 5 of Illinois, have invented certain new and useful Improvements in Bottle-Washing Machines, of which the following is a full, clear, and exact specification.

My invention relates to that class of bottle washing machines in which the result is accomplished by brushes engaging the bottles on either the inside or outside while a cleansing solution is injected.

The invention has for its primary object 15 to provide improved and simple means for carrying the bottles to a position where they will be engaged by the cleansing brushes and receive the cleansing solution, and after being thus operated upon, conducted out of 20 the way to make room for others.

With a view to the attainment of these ends and the accomplishment of certain other objects which will hereinafter appear, the invention consists in the features 25 of novelty which will now be described in connection with the accompanying drawings, and then more particularly pointed out in the claims.

In the said drawings Figure 1 is a vertical longitudinal sectional view of a bottle washing machine constructed according to this invention, and Fig. 2 is an end view thereof.

The bottles 1 to be washed are placed in 35 pockets or holders bottom side up, as indicated in Fig. 1, and these pockets or holders, any desired number of which and preferably a multiplicity of which are employed, are connected together in preferably an end- 40 less series forming an endless belt conveyer, and pass the point where the bottles are operated upon by the brushes or other cleansing devices. These holders may be constructed in any suitable way. In the example of the invention shown in the drawings, they are arranged to project inwardly 45 from the endless conveyer traveling in a vertical plane and so constructed and proportioned that when a bottle with a tapering neck is placed in an inverted position in a holder traveling under an upper horizontal portion of the conveyer, the shoulder or body of the bottle will be limited in its downward movement by a ring or collar 2 50 which is suspended by hangers 3, from a bar 4, which has an aperture 5 directly over each

of the collars 2. In practice it is desirable to employ a great multiplicity of these pockets, and to that end it is desirable that the bars 4 be as long as possible, consistent with 60 good mechanical construction, and supported transversely of the machine in as close relation to one another as feasible. These bars are secured at their ends to diametrically opposite links of two endless chain belts 6, 7, which are supported and travel around four pairs of sprocket wheels 8, 9, 10, 11, journaled in a suitable frame 12 on shafts 13, 14, 15, 16, which connect them together in pairs. 65

With the machine in the position shown in Fig. 1, the bottles to be washed are inserted in their pockets thus constituted on the chain belts 6, 7, at the left hand end of the machine, as each of the bars 4 rises to an 70 appropriate position, and while being thus supported neck downward, they are conveyed to the cleaning devices. In order that the bottles while being so held in their pockets may automatically register with the 75 cleaning devices and the entire operation of positioning them may be purely mechanical, it is preferable to impart to the chain belts 6, 7 an intermittent or step by step movement, causing them to move each time a 80 definite distance sufficient to carry one series of bottles away from the cleaning devices and present a new series to their action. To this end suitable mechanism, such as a pair 85 of pawls 17, is arranged to engage with the chains at some advantageous point, preferably with the rollers 18 which are journaled on the pivot pins at each end of each link and serve the further useful purpose of supporting the chains against downward deflections on side rails or tracks 19 mounted 90 upon the frame 12 or other support. These pawls 17 are pivoted respectively to the upper ends of two levers 20 which are fulcrumed upon the frame 12, and have their 95 lower ends arranged to be engaged by two cams 21 mounted upon a cross-shaft 22 in side members of the frame 12, and which cross-shaft 22 is rotated by any suitable connection, either with some other rotating 100 part of the machine, or in any other well known manner. At each revolution of the cams 21 the pawls 17 are thrust forward by the levers 20, and as the cams 21 recede from the levers 20, the pawls are returned by any 105 suitable means, such as springs 25 to engage another one of the rollers 18. 110

The bottles may be inserted into the intermittently moving conveyer thus constituted by hand, if desired, or by any manual or automatic means. In this example of the invention it is shown as associated with the conveyer or carrier of a bottle soaking machine of that type in which the bottles are carried on inclined pockets or supports 26 mounted upon a conveyer chain or belt 27, and from which the bottles are adapted to slide automatically after they pass below a retaining guard 28, whence they are directed by a chute 29 of suitable form into the apertures 5 of the bars 4 as the latter rise to the discharging end of the chute 29. If desired, the bottles may be retained in the chute 29 until the apertures 5 come into actual register therewith by any suitable detent 30 pivotally mounted and held in the path of the bottles by a spring 31 until tripped out of said path by pins or lugs 32 on the bars 4 striking a trigger 33, which overcomes the resistance of the spring 31 and compels the detent 30 to release the bottles. When the lug 32 passes, the spring 31 again returns an arm 34 of the detent against a stop 35, which positions the detent to receive and hold a new supply of bottles. Arranged to register with the rows of bottles where they stop at the conclusion of the movement of the pawl 17 are one or more rows of devices for injecting a cleansing fluid into the bottles and brushing them. There are many forms of devices for this purpose. The example of the same shown in the drawings as an element of this combination is the type in which the mouth of the bottle is engaged by a cup-shaped coupling member or clamping cap 36 having a stem 37 which forms a guide for a hollow spindle 38 having its upper end, where it enters the guide, split to form tentacles for scraping or brushing the interior of the bottle as the spindle 38 is projected upwardly through the guide 37, while the cap 36 is in contact with the neck of the bottle to prevent the cleansing fluid injected through the hollow spindle from escaping. The caps 36 are arranged in groups and normally positioned below the positions assumed by the mouths of the bottles when being operated upon by the cleaning device. There are as many hollow spindles 38 employed in this machine as there are apertures 5 in each of the bars 4, so that all of the bottles in each row as they stop in line with the spindles will be simultaneously operated upon, and if it is desired, additional rows of the spindles 38 may be provided so that when the bottles leave the first row of spindles to give place to the next row of bottles, the first row of bottles will go over a second row of spindles, and then over a third, and so on, as often as the rows of spindles are repeated throughout the travel of the conveyer. In this example of

the invention, but three rows of the spindles have been shown, the row referred to as 38 being the first, the row indicated at 38^a being the second and 38^b being the third. These spindles 38, 38^a and 38^b receive their supply of cleansing fluid from a chamber 39 mounted upon or forming a part of a frame 40 which is provided with as many conical nipples 41 as there are spindles. Engaging with these nipples 41 are shafts 42 whose lower ends are funnel-shaped for the purpose, and whose upper ends are connected with the spindles 38, and each of these shafts is provided with a driving means, such as a gear wheel 43, all of these being in train, 70 and the end one of the train driven by a gear 44 on an upright shaft 45 which receives its rotation from power shaft 46 connected with the shaft 45 by bevel gears 47, 48, whereby the spindles will be rotated while 75 the cleansing fluid is passing therethrough. The frame 40 which carries the shafts 42 and spindles 38 is vertically movable together with the gear wheel 44, which is splined on a shaft 45, so as to receive its rotation regardless of its position on the shaft, 80 it being carried with the gears 43 by suitable projections 49, 50 on the frame 40, as shown in Fig. 1. This causes the split ends of the spindles to project into the bottles as 85 said ends emerge from their guides 37. As the frame 40 rises with the spindles, the coupling members or caps 36 are forced upwardly out of their normal positions into engagement with the bottles by springs 51, 90 or other suitable elastic means. This is brought about by giving these springs 51 a support upon lugs 52 projecting inwardly from frame members 53 and supporting the caps 36 upon the springs. Any suitable 95 mechanism may be used for thus supporting the caps 36, but it is preferable to employ a plate or platform 54, which takes its support directly upon the springs and is provided with as many cages 55 as there are 100 guides 37, and into each of which cages projects one of the guides. Each cage is also provided with a spring or other cushioning member 56 inserted in the bottom thereof and engaging under the cap 36, this spring 56 being preferably coiled around the guide 37 so as to give each of the caps a resilient support independent of the springs 51. The springs 51 raise the cages 55 and their connecting bars as a whole, to bring the caps 36 against the bottles while each cap is enabled to yield individually by virtue of its spring 56 to accommodate itself to the position of the particular bottle with which it has to engage. After the cleansing 110 operation has been performed, the caps 36 are pulled downwardly away from the bottles by heads 57 on rods 58, which are secured to the frame 40 and project upwardly through the lugs 52, constituting guides therefor. These 115 120 125 130

rods also extend through the coil springs 51 and hold the latter in place. The frame 40 may be thus elevated for causing the spindles to project into the bottles by any suitable means. In this example of the invention each end of the frame is connected to the lower end of one of a pair of chains or other flexible members 59, which pass upwardly over sheaves 60 and are connected to two levers 61 respectively. The latter are pivoted at 62 to the frame 12 and are arranged to be engaged respectively by two cams 63 on the shaft 22. These cams, however, as well as the levers 61, are arranged out of the planes of the cams 21 and levers 20, so that the operation of the levers 20 and 61 will alternate, the construction and timing being such that after the cams 21 cause the bottles to move into position over the spindles, the cams 63 will lift the frame 40, as before described, and permit it to descend again before the cams 21 again come into operation.

The frame 40 which carries the internal spindles is shown with additional spindles 64 carrying brushes 65 so positioned as to engage the bottles on their exteriors and brush these surfaces, while the interiors are being operated upon, but these external brushes are not material to the present invention. After the bottles have been thus acted upon and pass around the pair of sprockets 11, they may be removed from the pockets of the carrier by hand, or allowed to fall out by gravity. If the latter method be employed, it is desirable to arrange a shield 80 in position to keep the bottles in the pockets until they arrive at a chute 66 sufficiently low down to insure their automatic discharge. As the caps 36 rise and engage the bottles, they of course exert a tendency to lift the same out of their pockets on the carrier, and to the end that this lifting tendency may be resisted, it is desirable to arrange over each row of bottles being acted upon a series of clamping caps 67 arranged in groups and equal in number to the number of bottles in each row and adapted to engage the bottoms of the bottles respectively. Each row of these caps is mounted upon a cross-bar 68 supported by transverse bars 69 serving to connect all three of the bars 68 together. Each end of the central bar 68 is provided with a nut 70 screw-threaded upon upright screws 71 mounted on the side frames of the machine in suitable bearings and provided with bevel gears 72 engaging with companion gears 73 on a cross-shaft 74 having a crank 75 whereby it may be rotated for causing all of the caps 67 to rise or descend to adjust their normal positions relatively to the coupling caps 36. The caps 67 are provided with cushioning means, such as springs 76, which permit them to be forced resiliently from

their adjusted normal positions to relieve undue pressure against the bottles. The upper and lower groups of the clamping caps are thus made adjustable in their adjusted normal positions relatively to each other.

I claim—

1. In a machine for the purpose described, the combination with an endless belt conveyer, of bottle holders carried by said conveyer, means for imparting intermittent motion to said conveyer, cleaning devices arranged to act upon the bottles at their periods of rest, a plurality of coupling caps below the bottle holders, and a plurality of caps above the bottle holders for resiliently clamping the bottles therebetween during the operation of the cleaning device, a cross bar from which said caps above the bottle holder are suspended resiliently, and means for adjusting both ends of said cross bar simultaneously with respect to the coupling caps below the bottle holder.

2. In a machine for the purpose described, the combination of an endless belt conveyer, bottle holders projecting inwardly from the inner face of the conveyer, said holders being adapted to carry the bottles inverted with their bottoms substantially flush with the outer face of the conveyer, means for delivering bottles endwise to said holders, said means being operable by each of said holders, cleaning devices co-operatively related to and encompassed by the conveyer, and means for alternately imparting movement to said conveyer and actuating said cleaning devices.

3. In a machine for the purpose described, the combination of an endless belt conveyer, bottle holders projecting inwardly from the inner face of the conveyer, said holders being adapted to carry the bottles inverted with their bottoms substantially flush with the outer face of the conveyer, means for delivering bottles endwise to said holders, said means comprising a chute, a plurality of pockets downwardly inclined for discharging bottles by gravity, and releasable means for retaining the bottles in said pockets until said pockets and bottle holders are in register, the last said means being operated by said endless belt conveyer to release the bottles from said pockets.

4. In a machine for the purpose described, the combination with an endless conveyer for bottles arranged in a vertical plane, said conveyer being adapted to receive bottles endwise in inverted position, of means for automatically feeding the bottles endwise thereto, said means comprising a chute arranged adjacent the conveyer, a second conveyer adapted to feed the bottles endwise under gravity to said chute, and provided with means for controlling the feed of said bottles, and means operated by the first said

conveyer for automatically operating said feed controlling means.

5. In a machine for the purpose described the combination of an endless series of bottle holders, means for imparting intermittent travel thereto, cleaning and rinsing devices for engaging the bottles while held in said holders, a feed chute arranged adjacent said holders for feeding the bottles thereto, 10 means for temporarily detaining the bottles in the feed chute, and means operatively related to the said series of holders for automatically releasing said bottle detaining means.
- 15 6. In a machine for the purpose described, the combination of an endless belt conveyer, bottle holders projecting inwardly from the inner face of the conveyer, said holders being adapted to carry the bottles inverted 20 with their bottoms substantially flush with

the outer face of the conveyer, means for delivering bottles endwise to said holders, said means comprising an auxiliary conveyer provided with downwardly inclined pockets, a chute interposed between the said 25 conveyers, said pockets being movable successively into register with said chute, detent means for temporarily detaining bottles in said chute, and means carried by each bottle holder for operating said detent means 30 to release a bottle.

In testimony whereof I have signed my name to this specification, in the presence of two subscribing witnesses, on this 29th day of March A. D. 1909.
